United States Patent

Des. 236,611

Patented Sept. 2, 1975

236,611

WHEEL

Robert Alan Carter, Sutton Coldfield, England, assignor
to Aluminum Bronze Company Limited, Wallows Lane,
Walsall, England

Continuation-in-part of abandoned application Ser. No.
383,907, July 30, 1973. This application July 26, 1974,
Ser. No. 492,025

Claims priority, application Great Britain June 14, 1973

Term of patent 14 years

Int. Cl. D12—16

U.S. Cl. D12—211

Fig. 1.

Fig. 2.

Fig. 3.

Fig. 4.

Fig. 5.

Fig. 6.

FIG. 1 is a front elevational view of a wheel showing my new design;

FIG. 2 is a sectional view thereof taken along the line 2—2 in FIG. 1 and looking in the direction of the arrows;

FIG. 3 is a fragmentary sectional view thereof taken along the line 3—3 in FIG. 1 and looking in the direction of the arrows;

FIG. 4 is a fragmentary sectional view thereof taken along the line 4—4 in FIG. 1 and looking in the direction of the arrows;

FIG. 5 is a fragmentary sectional view thereof taken along the line 5—5 in FIG. 1 and looking in the direction of the arrows; and

FIG. 6 is a rear elevational view thereof.

This is a continuation-in-part of my application Ser. No. 383,907, filed July 30, 1973, and now abandoned.

I claim:

The ornamental design for a wheel, as shown and described.
